UNITED STATES PATENT OFFICE

JOSEPH M. VAIL, OF BRYAN, OHIO

RAIL STAY

Application filed May 20, 1929. Serial No. 364,353.

This invention relates to a rail stay especially adapted to prevent creeping of railroad rails with relation to the ties. The desirability of using such a device is most apparent where there is a cumulative tendency for the rails to creep always in the same direction, as for example, in a double track system, where nearly all the traffic over any one pair of rails is in one direction.

The general object of the invention is to provide a stay particularly adapted for the purpose stated, which is simple in construction, which is strong and durable, which is easily and quickly applied, and which operates most efficiently.

The specific construction of the invention, in its present embodiment, its mode of operation, and the advantages thereof will be more particularly explained in connection with the accompanying drawings, illustrating the same.

In the drawings:

Figure 1 is a plan view of the invention as applied to a railroad rail, a portion of the latter being broken away.

Figure 2 is a section taken on the line 2-2 of Figure 1.

Figure 3 is a section taken on the line 3-3 of Figure 2.

Figure 4 is a section taken on the line 4-4 of Figure 1.

Figure 5 is a perspective view of a spring washer used in connection with the invention.

The invention is shown as applied to a railroad rail 6 having base flanges 7 resting on cross ties 8. It comprises a clamping member 9 adapted to extend underneath the rail and formed with an abutment 10 adapted to rest against the side of a tie 8.

The outer end of this clamping member is formed with an upwardly and rearwardly extending portion 11 having on its inner face an inclined surface 12 adapted to wedge against the correspondingly inclined surface of the flange 7. The opposite end of the member 9 is rabbeted to form a flat surface 13 opposed to the bottom surface of the rail base and spaced therefrom to receive the shank of a cooperating clamping member 14.

The member 14 is formed with a downwardly and rearwardly extending flange portion 15 with an inner inclined surface 16 adapted to wedge against the correspondingly beveled surface on the end portion of the member 9. The member 14 also has an upwardly and rearwardly extending flange portion 17 opposed to the flange portion 11 of the member 9 and having an inner inclined face 18 adapted to wedge against the correspondingly inclined surface of the rail flange 7.

In order to aid in drawing the clamping members 9 and 14 into clamping relation to the rail base, one of the clamping members, as 9, is formed with a stud 19, which extends upwardly above the face 13 and is engageable with a laterally inclined slot 20 in the other member 14. Thus, as the member 14 is driven toward the left as viewed in Figure 1, the stud 19 rides toward the inner end of the slot 20 and forces the two clamping members inwardly, wedging the flanges 7 between them.

In order to secure the clamping members more firmly to the rail, a channel 21 is formed about the stud 19 and is adapted to receive a spring washer or collar 22. The intermediate portion of this washer or collar is substantially circular and terminates in a straight end portion 23, the channel 21 having a correspondingly shaped extension 24 to receive the same. The other end 25 of the collar is raised and is in position to engage a beveled surface 26 formed on the clamping member 14, as the latter is driven into position. As the end 25 of the collar rides on this beveled surface 26, it is forced downwardly into the channel 21 and exerts a very powerful upward pressure against the shank of the member 14. The latter may be formed with a roughened or serrated surface 27, to be engaged by the end of the collar, thus constituting ratchet means to prevent the clamping members from becoming separated after they are driven into position. In order to facilitate the driving of the clamping members into clamping relation to the rail, one of the clamping members, as 14, is formed with a nose 28 to receive

the blows of a sledge, while the abutment 10 formed on the other member rests against the side of the tie.

From the foregoing description, it will be seen that I have provided a very simple, strong and efficient clamping device which will grip the rail with very great pressure and cannot slip or become detached therefrom. The stud 19 working in the slot 20 draws the two clamping members inwardly, while at the same time the spring washer 22, which is very strong, forces the shank of the member 14 with very great pressure against the bottom of the rail, so that the clamping device cannot slip. In a double track system, the clamping device is applied with the abutment 10 against the side of a tie which will resist movement of the rail in the direction in which it has a tendency to creep. In a single track system, where it is desired to hold the rail against creeping in both directions, another clamping device may be applied to the same or another rail and turned in the opposite direction.

While I have shown and described in considerable detail one embodiment of the invention, it is obvious that the same may be considerably modified without departing from the scope of the appended claims.

What I claim is:

1. In a device of the character described, a pair of opposed clamping members, means for forcing said members inwardly with a rail gripped between them, and a resilient member operable at the same time to force one of said members against the rail in a direction transverse to the inwardly directed force.

2. In a device of the character described, a pair of opposed clamping members, means for forcing said members in a substantially horizontal direction against a rail disposed between them, and a resilient member operable at the same time to force one of said members in a substantially vertical direction against the rail.

3. In a device of the character described, a pair of opposed clamping members adapted to engage the opposite base flanges of a rail, co-engaging means including a stud on one of said members and a laterally inclined slot in the other member for receiving said stud to draw said members toward each other and into clamping engagement with the rail as one member is driven longitudinally with respect to the other, and an expansile ratchet member acting between the two clamping members to maintain their engagement with the rail.

4. In a device of the character described, a pair of opposed clamping members adapted to engage the opposite base flanges of a rail, an abutment on one of said members engageable with the edge of a cross tie,

while the other member is driven toward the same, co-engaging means for forcing said members into clamping relation to the rail during such driving operation, and an expansile ratchet member acting between the two clamping members to maintain their engagement with the rail.

5. In a device of the character described, a pair of opposed clamping members adapted to clamp to the opposite flanges of a rail, with shanks extending beneath the rail in overlapping relation to each other, means on one of said members engageable with the shank of the other member to prevent the two shanks from spreading, and resilient means engageable between the two shanks to prevent relative horizontal slipping thereof.

6. In a device of the character described, a pair of clamping members provided with normally overlapping shanks and overhanging flanges adapted to engage about the base flanges of a rail, wedge means to increase the clamping pressure as one of said members is driven with respect to the other, and a resilient ratchet member acting between the two clamping members to lock them in clamping position.

7. In a device of the character described, a pair of clamping members provided with normally overlapping shanks and provided with means for forcibly engaging opposite base flanges of a rail when the two members are drawn together, and a resilient member acting between the overlapping portions to maintain such forcible engagement.

8. In a device of the character described, a pair of clamping members provided with normally overlapping shanks, means, including a projection on one of said members and a laterally inclined slot in the other receiving such projection, for causing said members to forcibly clamp the rail when one of them is shifted longitudinally with respect to the other, and a resilient member acting between the overlapping portions to maintain such forcible engagement.

9. In a device of the character described, a pair of clamping members provided with normally overlapping shanks, means, including a projection on one of said shanks and a laterally inclined slot in the other shank receiving said projection, for causing said members to forcibly clamp the rail when one of them is shifted longitudinally with respect to the other, and an expansile member acting between the shanks to increase the upward pressure of one of the shanks against the bottom of the rail during such longitudinal shifting.

10. In a device of the character described, a pair of clamping members provided with normally overlapping shanks, means, including a projection on one of said shanks and a laterally inclined slot in the other shank

receiving said projection, for causing said members to forcibly clamp the rail when one of them is shifted longitudinally with respect to the other, a resilient element between the two shanks, and means cooperating with said resilient element to cause an increased upward pressure of one of the shanks against the bottom of the rail during such longitudinal shifting.

5 10 In testimony whereof I have hereunto signed my name to this specification.

JOSEPH M. VAIL.
